UNITED STATES PATENT OFFICE.

ELLERSON L. BRAINARD, OF DANBURY, CONNECTICUT.

DESIGN FOR A STANDARD FOR LIGHTS, CLOCKS, OR SIMILAR ARTICLES.

SPECIFICATION forming part of Design No. 36,751, dated January 26, 1904.

Application filed December 5, 1903. Serial No. 183,980. Term of patent 3½ years.

To all whom it may concern:

Be it known that I, ELLERSON L. BRAINARD, a citizen of the United States of America, residing at Danbury, in the county of Fairfield and State of Connecticut, have invented a new, original, and ornamental Design for a Standard for Lights, Clocks, or Similar Articles, of which the following is a specification.

The drawing shows a perspective view of a standard made according to my design.

I claim as new and desire to secure by Letters Patent—

The ornamental design for a standard for lights, clocks, and similar articles, substantially as described.

ELLERSON L. BRAINARD.
